UNITED STATES PATENT OFFICE.

OTIS TIFFANY GREGG, OF HACKENSACK, NEW JERSEY, ASSIGNEE TO THE GREGG COMPANY, LIMITED, OF HACKENSACK, NEW JERSEY, A CORPORATION OF NEW YORK.

CAR-COUPING.

1,156,073.

Specification of Letters Patent. Patented Oct. 12, 1915.

Original application filed May 17, 1913, Serial No. 754,935. Divided and this application filed October 13, 1913. Serial No. 784,886.

To all whom it may concern:

Be it known that I, OTIS T. GREGG, a citizen of the United States, residing at Hackensack, in the county of Bergen and State of New Jersey, have invented certain new and useful Improvements in Car-Couplings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to car couplers, and has for its object to provide a coupler which shall embody so far as possible the maximum of strength with the minimum of metal and in which the component parts will be retained in their respective positions or places without liability of becoming accidentally displaced or lost, and under which the movable parts will be effectively shielded or protected against injury or damage from the outside.

To the accomplishment of the foregoing and such other objects as may hereinafter appear the invention consists in the features hereinafter particularly described and then sought to be clearly defined by the claims, whereby the coupling link not in use may be safely housed so as to be protected from injury and be prevented from interfering with the proper action of other parts; also in features of construction whereby the coupling pin of one car is permanently retained in operative relation to associated parts so that the coupling pin remains always connected with the draw-head while the link of the other car to be coupled may be readily engaged by the coupling pin of the car; also in features of construction in which the coupling pin may have a movement to either side of the center of the openings formed in the draw-head to receive the coupling pin so that the pull on the coupling pin may be in a more direct line with longitudinal sills of a car and the couplers be afforded a greater range of side movement than heretofore, and also to facilitate the coupling of two cars.

Reference is to be had to the accompanying drawings forming a part hereof, and in which:

Figure 1 is a perspective of the draw-head

part of the coupler; Fig. 2 a vertical longitudinal section through the coupler, the coupling pin being in full lines; Fig. 3 a horizontal central section through the coupler; Fig. 4 a vertical cross section through the coupler, the links and pin being in full lines.

In the drawing the numeral 1 designates a draw-head having a rearwardly extending shank 2 which will fit in a suitable housing (not shown) adapted to be bolted or otherwise secured to a car.

The draw-head is made with a recess or chamber 3 beneath its top and preferably formed by a depending flange 4, said chamber extending crosswise of the draw-head and adapted to receive and shield a permanently attached coupling link 5 so that when said link is not in use and two cars are coupled together said link will be confined within the chamber or recess 4 and thus protected against injury and prevented from projecting outside of the draw-head. The draw-head is also formed with a recess or chamber 6 in its lower face, preferably formed by an upwardly extending flange 7, so that the permanently attached coupling link may be seated in said recess or chamber and shielded from injury and prevented from projecting outside of the draw-head when the car is uncoupled from another car, said lower recess or chamber extending cross-wise of the draw-head similarly to the afore-mentioned upper recess or chamber. The space 8 between the depending flange 4 and the upper extending flange 7 is less in depth than the combined thickness of two coupling links 5 and 15 so that when two cars are coupled together the permanently attached link lying within the upper recess or chamber 3 cannot pass or drop below the lower edge of the flange 4, and thus the idle link is kept in the top chamber so that it cannot pass through the space 8 and project outside of the draw-head when two cars are coupled together. It will also be observed from an inspection of Figs. 2 and 4 of the drawing that if the active link 15 or the link in use tilt as shown in the illustration its inner end will press upward beneath the idle link and tend to hold the idle link within its recess or chamber as shown.

Another feature of the invention lies in making oblong in the direction of the width

22 of the draw-head the holes or slots 9 and 10 formed respectively in the top and bottom members of the jaw of the draw-head to receive the coupling pin 11, said oblong holes 5 extending to opposite sides of the longitudinal center line of the draw-head so as to provide for the coupling pin to lie either in the center of the holes or to either side of the center so that the pull on the coupling 10 pin may be in a more direct line with the longitudinal axis of the coupler and thus lessen the diagonal direction of pull on the coupling pin which occurs when cars travel on curves. This feature of construction also 15 makes it possible to more readily and easily couple two cars together when the couplers are not in exact alinement with each other and also allows the couplers greater side play or movement under conditions in which 20 it is desirable to provide for the same. Another feature of the invention lies in permanently connecting the coupling pin to the draw-head in a manner that will admit of it being manipulated so as to be passed 25 through and withdrawn from the active coupling link without being released from the idle link, thus insuring the coupling pin and idle link always being attached to the draw-head, and making one coupling 30 pin answer the two-fold purpose of permanently securing the idle link to the draw-head and of engaging the active link when two cars are coupled together. To this end the coupling pin is formed with a shoulder 35 or head 12 at its lower end and encircled by a washer 13 which is free to slide on the coupling pin but not to pass over the shoulder or head 12 at one end of the pin, and is incapable of passing through the 40 coupling links, the opposite or upper end of the pin, after the pin is placed in position and passed through the washer and the idle link, being provided with a head 14 which may be threaded or secured by a pin or 45 otherwise to the coupling pin so as to rest on top of the draw-head about the opening 9 formed therein, the head being of such dimensions that it cannot pass downwardly through the opening 9. The idle link and 50 the washer are thus attached by the coupling pin to the draw-head, and the coupling pin is thus connected to the draw-head so that while it may have a vertical movement it cannot become detached from the draw-head and yet it is free to be passed through 55 the link which for the time serves as the coupling link between the two cars. The side-walls, either upper or lower, or both, of the lower opening 10 for the coupling 60 pin are beveled or flared so as to facilitate the lower shouldered end of the coupling pin being directed to the opening for easy

passage therethrough in either lifting or lowering the coupling-pin.

The particular features of construction 35 described provide a coupler possessing the several advantages specified, and besides giving the maximum strength also make it possible to more conveniently manipulate the parts in coupling and uncoupling. 70

By draw-head as used herein it is not to be understood as confined to a two-part draw-head construction as some features of the invention are equally applicable whether the draw-head be a one-piece coupler or more 75 than one.

This is filed as a division of my application filed March 17, 1913, Serial No. 754,935.

Having described my invention and set forth its merits what I claim is:—

1. In a car coupler, a draw-head, and a coupling link, the top of the draw-head having formed on its under-face a recess or chamber extending cross-wise of the head of a sufficient depth to receive the link and of a length, cross-wise of the head, not less than the greatest length of the link, substantially as described. 80

2. In a car coupler, a draw-head, and a coupling link, the top of the draw-head having formed on its underface a recess or chamber extending cross-wise of the head, and the bottom of the draw-head formed on its upper face with a recess or chamber extending cross-wise of the head, each of said chambers being of sufficient depth to receive the link and of a length, cross-wise of the head, not less than the greatest length of the link, substantially as described. 90

3. In a car coupler, a draw-head, and a coupling link, the top of the draw-head having formed on its under-face a recess or chamber adapted to receive said link, and having an opening formed in its front face extending the width of the head for the passage of an additional link, said opening in depth being less than the combined thickness of the two links, substantially as described. 100

4. In a car coupler, a draw-head, and a coupling-pin, the draw-head being formed with upper and lower openings for the coupling-pin, said openings being elongated in the direction of the width of the draw-head to permit the pin to move to either side of the center of the opening toward either side of the draw-head, substantially as described. 110

In testimony whereof I affix my signature in presence of two witnesses.

OTIS TIFFANY GREGG.
